UNITED STATES PATENT OFFICE

LAWRENCE R. MCAFEE, OF BELLEVUE, PENNSYLVANIA, ASSIGNOR TO RELIANCE STEEL PRODUCTS COMPANY, OF PITTSBURGH, PENNSYLVANIA, A CORPORATION OF PENNSYLVANIA

FURNACE DOOR FRAME

Application filed November 19, 1929. Serial No. 408,320.

My invention relates to improvements in furnace door frames, and more particularly to furnace door frames of the character employed in open-hearth furnaces and the like. 5 The prime object of the present invention is to provide a new and improved door frame of the type above specified, which may be formed of seamless or lap-welded tubing or the like, and other hollow members, as distinguished from cast metal and sheet metal structures, assembled and secured together to form a skeleton frame of efficient construction embodying passages for the desired circulation of a cooling fluid therein. 15 Further objects are, to provide a frame of skeleton construction, of relatively light weight, that may be readily applied to and removed from a furnace without dismantling the furnace; to provide a frame of the character specified having an efficient and simple water circulating system; a construction free of seams and their accompanying disadvantages; and a structure embodying, in combination with the seamless tubes, a structural 20 steel member functioning to provide a rigid frame, and means for securing the frame to a furnace wall.

Additional objects and advantages will become apparent from the following specification, taken in connection with the accompanying drawings, wherein:

Fig. 1 is an elevational view partly broken away, of a door frame embodying my invention;

Fig. 2, a top plan view thereof;

Fig. 3, a vertical sectional view taken on the line III—III of Fig. 1, showing the means for securing the frame to the furnace structure;

Fig. 4, an enlarged detail sectional view taken on the line IV—IV of Fig. 2, particularly showing the closure means for the upper end of a frame member;

Fig. 5, a perspective view of the upper end of a frame member, showing the closure means detached;

Fig. 6, a horizontal section on the line VI—VI of Fig. 1; and

Fig. 7, a vertical section on the line VII—VII of Fig. 6.

Referring to the drawings, 2 designates the leg members of the skeleton frame. Members 2 are of sufficient length to extend from the bottom of the furnace door opening A to points well above the top of said opening, and are designed to be positioned one on each side of the opening A.

As illustrated and as preferred, members 2 are formed of open-ended seamless drawn tubing, having a rectangular cross section, 60 and each is provided with a passage 3 for the circulation of a cooling fluid therethrough. 4 designates a lintel or the lintel portion of the frame. This lintel portion, as shown, is of U-shape in configuration, thus providing 65 a central arched portion and depending lintel legs 5, and is preferably formed of a seamless tube having a rectangular cross-section of somewhat smaller area than the legs proper.

The lintel portion 4 is placed between the leg members 2 in such a manner that the lower ends of the lintel legs 5 and the leg members 2 coincide, and openings 6 in the outer walls of the lintel leg portions register 75 with similar openings 7 in the innermost walls of the leg members 2, the rear walls of the lintel legs and leg members being in alignment. In this position, the leg portions of the lintel and leg members are secured together by stitch-welding along their front and rear meeting edges, as at a, and by welding between said members and leg portions, as at b. In addition, the meeting walls bordering the openings 6 and 7 are welded, as at 80 c, to provide a communicating fluid passage between the passage 3 and an interior fluid passage 8 of the said lintel, at each side of the frame.

The open lower ends of the portions 5 and the members 2 preferably have their edges beveled inwardly, as at 9, and are adapted to receive closure members or plates 10. Said plates have their edges 11 beveled oppositely to the edges of the portions 5 and members 2, so that when the plates are inserted within the ends thereof, a V-shaped groove is formed to receive a welding metal d for securing the plates to said lower ends, and thereby seal them.

The open upper ends of the leg members 2 are designed to be closed by closure members or caps 12, and for this purpose the edges of the legs are beveled, as at 13, for receiving the welding metal *e* between said edges and the oppositely beveled edges 14 of the caps 12. The caps are each formed with an apertured extension 15 threaded to receive a fluid inlet conduit 16.

10 A vertically extending tubular member 17 projects upwardly from the arch of the lintel portion 4, and is preferably formed of seamless tubing of the same cross-section as that comprising the lintel. Tubular member 17 is centrally located with respect to the leg members 2, and is welded to the upper wall of the lintel portion, as at *f*, said wall being provided with an opening 18 therethrough to effect communication between the passage 8 and a passage 19 of the member 17.

15 The upper end of the member 17 preferably terminates in the same plane as the upper ends of the leg members 2, and is adapted to be closed by means of a closure

20 member or cap 12a, the latter having an extension 15a threaded to receive an outlet conduit 20. Said cap 12a is beveled and welded to the upper edges of the tubular member in the manner hereinbefore described.

25 For the purpose of anchoring the tubular members into a strong and durable skeleton frame, and to provide means for securing the frame to the furnace, I provide a structural member 21 adapted to receive the upper ends of said members. For example, I have

30 shown the member 21 in the form of a Z-bar, having its upper flange 21a co-extensive with the upper ends of the tubular members. Said upper flange is cut away or recessed as at 22

35 to permit the entrance of the leg members and the member 17. The recesses are of sufficient depth to allow the back walls of said members to contact with the front face of the intervening web 23 of the Z-bar.

40 45 When the members are so positioned, they are welded to the Z-bar, as at *g* (see Fig. 5).

The other flange of the Z-bar extends rearwardly and may be employed for securing the frame to the furnace structure by bolts

50 or other suitable means. However, I have shown an alternative method, which consists of clips 24 welded or otherwise secured to the front face of the Z-bar web 23, having openings therein to receive J-bolts 25. The hook

55 portions of said bolts are adapted to engage a flange of the skew channel 26 of the furnace structure, thereby providing a simple and durable mounting for the frame on the front wall of the furnace.

60 Due to the different cross-sectional sizes of the lintel portion and the leg members, and the positioning thereof, a guide or trackway 27 is provided in the front portion of the frame, which may be employed for guiding a

sliding door 28, shown in the broken lines of Fig. 2.

65 As indicated by the arrows of Fig. 1, the fluid circulation is as follows. Water or other cooling medium is introduced into the 70 passages 3 of the leg members 2 by means of the inlet conduits 16, and passed downwardly, entering the passage 8 of the lintel portion through the openings 6 and 7. The water 75 then passes upwardly through the passage 8 and enters the passage 19 of the member 17, and thence upwardly therein, discharging by means of outlet conduit 20. By reason of the rectangular cross section of the members, and the circulation just described, 80 the steam pockets encountered in present practice are eliminated. The embodiment of seamless tubing in a skeleton frame of the character described, minimizes the possibility of damage to the frame by being struck by 85 the furnace charging machine or other heavy objects. The strength of the tubular sections will be readily understood and should they be struck in the said manner, they will only be deformed or dented, which will not result 90 in the destruction of the frame.

95 It will be seen from Fig. 1 that the skeleton construction of my frame provides openings B therethrough above the lintel portion. These openings permit repair of the furnace 100 wall without the removal of the frame, and also may be employed for the insertion of a supplemental wall or brick-work in the event that the front wall of the furnace fails during operation, without shutting down the 105 furnace.

110 While I have shown one form of door frame and one form of seamless tubing, it will be understood that various modifications thereof are contemplated, provided they fall within 115 the scope of the following claims.

I claim:

1. A water cooled furnace door frame of skeleton construction comprising leg and lintel portions formed of tubing, said leg 110 portions extending above said lintel portions, said lintel portions having depending legs 115 united by welds to the frame legs proper, plates closing said leg portions and lintel portions at the bottom, structural means 120 spaced above the lintel portion connecting the frame leg portions, means placing the legs of the frame in communication with the depending legs of the lintel portion at the bottom, and inlet and outlet means at the top of the 125 leg and lintel portions respectively.

2. A water cooled furnace door frame of skeleton construction comprising communicating leg and lintel portions formed of tubing, said leg portions extending above and 130 below the lintel portion, said lintel portion having depending legs united by welds to the frame legs proper at the lower portions of the legs, plates welded to the lower ends of said frame and lintel legs to close them and 135

connect the portions, a cross structural member spaced above the lintel portion and connecting the upper ends of the legs, and means for causing a circulation of water through 5 the tubular members.

3. A water cooled furnace door frame of skeleton construction comprising leg and lintel portions formed of tubing, said lintel portion being of U-shape and having its depending leg portions united by welds to the legs proper, said legs proper projecting above the lintel, and plates closing the frame and lintel legs at the lower ends, a vertically extending tubular member projecting from the lintel and in open communication therewith, and means to provide a circulatory communication through the tubular parts.

4. A water cooled furnace door frame of skeleton construction comprising leg and lintel portions formed of tubing, said lintel portion being of U-shape and having its depending leg portions united by welds to the legs proper, plates closing the lower ends of the frame and lintel legs at the lower ends, said legs proper projecting above the lintel, a vertically extending tubular member projecting from the lintel and in open communication therewith, means to provide a circulatory communication through the tubular parts, and a cross structural member connecting the upper ends of said vertically extending tubular member and the legs.

5. A water cooled furnace door frame of skeleton construction comprising leg and lintel portions formed of seamless tubing of rectangular cross section, said lintel portion being of U-shape and having its depending leg portions united by welds to the legs proper, plates welded to and closing the lower ends of the frame and lintel legs at the lower ends, said legs proper projecting above the lintel, means to provide a circulatory communication through the tubular parts, and a cross structural Z-member formed to receive the upper ends of the leg extensions into which the said ends are entered.

6. A water cooled furnace door frame comprising leg and lintel portions formed of tubing, said leg portions extending above and below the lintel portion, lintel leg portions disposed adjacent the lower ends of said leg portions, means for closing and connecting the legs and lintel leg portions at the bottom, means placing the leg portions and the lintel leg portions in communication at the bottom, inlet and outlet means at the top of the leg and lintel portions respectively to provide a downward passage of a cooling fluid through a leg and an upward passage of the fluid through the lintel legs and lintel, and structural means spaced above the lintel portion and connecting the leg portions.

7. A water cooled furnace door frame comprising leg and lintel portions formed of tubing, said leg portions extending above and be-

low the lintel portion, lintel leg portions disposed adjacent the lower ends of the said leg portions, means for closing and connecting the legs and lintel portions at the bottom, means placing the leg portions and the lintel 70 leg portions in communication at the bottom, a fluid inlet for a leg portion, a vertically extending tubular fluid outlet member projecting from the lintel and in open communication therewith, and a structural member 75 spaced above the lintel portion and connecting the tubular fluid outlet member and the leg portions.

In testimony whereof I affix my signature.
